MANFOLDING MACHINE

William C. Pfeiffer, Dayton, Ohio, assignor to The Egry Register Company, Dayton, Ohio, a corporation of Ohio

Original application February 5, 1936, Serial No. 62,463. Divided and this application May 22, 1937, Serial No. 144,135

5 Claims. (Cl. 197—2)

This invention relates to typing or manfolding machines and the like, and particularly, to devices for making supplemental copies of the record simultaneously with the making of the usual copies.

One object of this invention is to provide a typing or similar printing machine having means for producing additional copies of the records at the same time that the regular copies are made.

Another object is to provide a typing or similar printing machine in which a record strip moves transversely to the sheets employed in making the regular copies, this record strip being interposed between the type bars and the regular copies.

Another object is to provide means for making an additional copy of records produced in a machine of the type described, wherein the machine itself moves over a work bed containing the work sheets, the feeding of the strips for the supplemental record being linked up with and synchronized with the mechanism of the typing or manfolding machine.

Another object is to provide mechanism of the type previously described for making an additional copy of records produced in typing or manfolding machines, such apparatus being capable of being employed in connection with machines having type bars which engage the record sheets beneath the platen.

This application is a division of my copending application, Ser. No. 62,463, filed February 5, 1936.

The drawing shows an elevation, partly in cross section and partly broken away, of a machine capable of being moved bodily to and fro over the work, and having means for making a supplemental record in addition to the regular records.

General construction

In general, the apparatus of my invention makes use of a strip of material, either having a carbon coating on the back thereof, or having a separate carbon strip associated therewith, the assembly being made to traverse the typing machine in a direction transverse to the direction of motion between the typewriter and the sheets of paper employed for making the regular copies.

The supplemental copy strips are adapted to make copies of records made on the regular copies, these supplemental copy strips containing certain key information which it is advisable to obtain immediately, rather than to wait until the regular copies are returned to the person de-

siring this information. For example, it is often advisable to obtain production or shipping records, such as the name and address of the customer, the quantity and nature of the goods ordered, the time of delivery and such credit information as may be necessary. These data are recorded in a small area on the regular carbon sheets and simultaneously recorded upon the supplemental record strip, which moves transversely thereto. The supplemental record strips may be torn off from time to time, and the information thereon transferred to the person requiring it without the necessity of sending that person complete copies of the entire forms made by the machine as a whole.

The feeding mechanism for the supplemental copy strips is operatively connected to the typewriter mechanism in such a manner that the two machines are synchronized to work in unison. In a preferred embodiment the feeding mechanism is operated by devices actuated by the motion of the platen of the machine.

In the type of machine shown in the drawing the entire typing assembly is moved to and fro over the work. The record sheets 5 and interleaved carbon sheets 6 are shown mounted upon a horizontal bed 10, having rails 11 upon which a framework 12 is movably supported, as by the rollers 13. Arranged to move longitudinally along the framework 12 and between the rollers 13, is the typing machine, generally designated 14, and having keys, 15 which by suitable mechanism transmit their motion to the type levers 16, operating the downwardly-moving type faces 17.

Mounted on the machine 14 are pack holders 18 and 19, respectively, the former being adapted to hold the paper pack being withdrawn and the latter to receive the strips after they have been inscribed. The typing machine 14 is also provided with shafts 20 and 21, on which are mounted ribbon spools 22 and 23, adapted to hold a ribbon 24. The assembly, comprising the record strip 3 and the carbon strip 4, is threaded over the guide roller 25, between the rollers 26 and 27, and around the guide roller 28 into the space between the ribbon 24 and the record sheets 5 and 6 on the bed 10. Beyond these the record strip 3 and carbon strip 4 continue around the guide roller 29, and between the feed rollers 30 and 31.

The rollers 26, 27, 30 and 31 are mounted upon the shafts 32, 33, 34 and 35, respectively. The shafts 34 and 35 are geared together, in a manner analogous to that previously described, and are driven such as by the intermeshing pinions 36 and 39. The shaft 34 carries a sprocket 40.

- The frame 12 is provided with a rack 41, which meshes with the corresponding teeth of a gear 42, mounted upon the shaft 43 supported by the bracket 44 on the typing machine 14. The gear 42 drives a ratchet 45 through a pawl 46, the ratchet 45 being drivingly connected to the sprocket 47. The latter drives the sprocket 40 upon the feed roller shaft 30 through the intermediate agency of the sprocket chain 48.
- 10 In the operation of the apparatus shown in the drawing the machine 14 moves bodily to the right, as the operator operates the keys 15. When this occurs, the motion of the machine 14 causes the rotation of the gear 42 by its engagement with the rack 41 upon the frame 12, and the sprockets 40 and 47 cause the consequent rotation of the feed rollers 30 and 31 so that the assembly comprising the supplemental record strip 3 and the carbon strip 4 is fed through the machine, past the type faces 17 and out into the receiving holder 10. By selecting the proper ratios in the various gears and sprockets it will be seen that the supplemental record strip 3 and its accompanying carbon strip 4 can be fed at an equal speed but opposite direction of the machine 14, so that during the typing operation the strips 3 and 4 remain stationary relatively to the record sheets 5.
- 20 When the machine 14 is retracted, however, in order to begin typing a new line, the pawl 46 slips over the ratchet 45, causing the feed rollers 30 and 31 to become temporarily inactive. During the retraction of the machine 14, therefore, the strips 3 and 4 move bodily as a unit with the machine 14, hence, travel relatively to the record sheets 5. When the typing of the new line begins and the machine 14 again moves to the right, the feed rollers 30 and 31 again become operative, and the strips 3 and 4 again are fed relatively to the machine 14 at an equal speed in the opposite direction.
- 30 Optionally, the supplemental record may consist of a strip of thin cardboard, preferably perforated at intervals so that the strip may be separated into index cards and filed in any suitable manner. The main record sheets may be in continuous web form and provided with interleaved carbon sheets, with or without a conventional carbon sheet carrier for moving the carbon sheets back into position for another typing, after one set of forms has been typed.
- 40 It will be understood that I desire to comprehend within my invention such modifications as come within the scope of the claims and the invention.
- 50 Having thus fully described my invention, what I claim as new and desire to secure by Letters Patent, is:
- 60 1. In combination, a bed, guides on said bed, a typing machine movable on said guides relatively to said bed for typing a main record supported on said bed, means on said typing machine and movable therewith for supporting a continuous supplemental record strip in zigzag folded pack form for motion in a path across said main record, and means responsive to the motion of said typing machine for feeding said supplemental record strip past the type members thereof, said supplemental record strip having a width adapted for receiving a single line only of typed characters and being disposed in the same direction as the line of characters being typed.
- 65 2. In combination, a bed, guides on said bed, a typing machine movable on said guides relatively to said bed for typing a main record supported on said bed, means on said typing machine and movable therewith for supporting a continuous supplemental record strip in zigzag folded pack form for motion in a path across said main record, means for receiving the record strip after the record has been inscribed thereon, and means responsive to the motion of said typing machine for feeding said supplemental record strip past the type members thereof, said supplemental record strip having a width adapted for receiving a single line only of typed characters and being disposed in the same direction as the line of characters being typed.
- 70 3. In combination, a bed, guides on said bed, a typing machine movable on said guides relatively to said bed for typing a main record supported on said bed, type members moved in response to the operation of said typing machine, means responsive to the motion of said type members for moving said machine step-by-step relatively to said bed, means on said typing machine and movable therewith for supporting a continuous supplemental record strip in zigzag folded pack form for motion in a path across said main record, and means responsive to the motion of said typing machine for feeding said supplemental record strip past the type members thereof, said supplemental record strip having a width adapted for receiving a single line only of typed characters and being disposed in the same direction as the line of characters being typed.
- 75 4. In combination, a bed, guides on said bed, a typing machine movable on said guides relatively to said bed for typing a main record supported on said bed, type members moved in response to the operation of said typing machine, means responsive to the motion of said type members for moving said machine step-by-step relatively to said bed, means on said typing machine and movable therewith for supporting a continuous supplemental record strip in zigzag folded pack form for motion in a path across said main record, means responsive to the motion of said typing machine for feeding said supplemental record strip past the type members thereof, and means responsive to the motion of said type members for moving said supplemental record strip, said supplemental record strip having a width adapted for receiving a single line only of typed characters and being disposed in the same direction as the line of characters being typed.
- 80 5. In combination, a bed, a typing machine arranged to move over said bed for typing a main record supported on said bed, means for supporting a supplemental record in zigzag folded pack form in a path across said main record, and means responsive to the motion of said typing machine for feeding said supplemental record past the type members thereof, said supplemental record-supporting means being arranged on opposite lateral sides of said typing machine and movable as a unit therewith, said supplemental record strip having a width adapted for receiving a single line only of typed characters and being disposed in the same direction as the line of characters being typed.
